UNITED STATES PATENT OFFICE.

FERDINAND BUCHHOP AND ALFRED J. ALLIBONE, OF NEW YORK, N. Y.,
ASSIGNORS TO EMIL B. MEYROWITZ, OF RIDGEFIELD, NEW JERSEY.

SPECTACLE-TEMPLE AND MODE OF MAKING THE SAME.

SPECIFICATION forming part of Letters Patent No. 440,220, dated November 11, 1890.

Application filed February 27, 1890. Serial No. 342,022. (No model.)

To all whom it may concern:

Be it known that we, FERDINAND BUCHHOP and ALFRED J. ALLIBONE, citizens of the United States, and residents of New York, in the State of New York, have jointly invented a new and useful Improvement in Spectacle-Temples and the Process of Making the Same, of which the following is a specification.

This invention consists, primarily, in hook-temples of novel construction, the hook portion of each being composed of two or more intertwined strands so as to render it very strong and resilient, and having at the same time a practically unbroken cylindrical exterior whereby it is rendered smooth and comfortable to the wearer, while the diameter of the relatively stiff straight portion or main portion of the temple is merged into that of the hook portion so as to avoid any unsightly and uncomfortable shoulder or enlargement where the two unite.

The invention further consists in the peculiar process whereby such hook-temples are produced and certain novel features thereof, as hereinafter set forth and claimed.

A sheet of drawings bearing eight figures accompanies this specification as part thereof.

Figure 1 of the drawings is a side view of a finished hook-temple, illustrating this invention. Figs. 2, 3, 4, 5, and 6 are side views, more or less shortened by breaks, illustrating the process of manufacture; and Figs. 2^a and 3^b are respectively cross-sections on the lines *a a* and *b b*, Figs. 2 and 3, Figs. 1 and 4 to 6 being drawn to one scale, Figs. 2 and 3 to a larger scale, and Figs. 2^a and 3^b to a still larger scale.

Like letters of reference indicate corresponding parts of the product and blanks or stock in the several figures.

The finished temple, Fig. 1, is composed of, first, a straight or substantially straight and relatively stiff main portion *A*, having conveniently the half-hinge *h* integral therewith; second, a hook portion *B*, composed of intertwined strands, but with a substantially unbroken cylindrical exterior, as represented in Fig. 3^b, and, third, a tip *C*, preferably recurved, as shown, to keep said portion *B* from untwisting and to fit comfortably behind the ear of the wearer, all said parts being inseparably

united, and the diameter of said main portion *A* being tapered or merged into that of said hook portion *B*, so that there is no unsightly and uncomfortable break in the surface where the two adjoin. To produce such a temple, we proceed, as illustrated by Figs. 2 to 6, inclusive, as follows: The blank of the main portion *A*, roughly shaped, as shown in Fig. 4 only detached, is gotten out by swaging, with or without the aid of dies, in customary manner. After, or in addition to getting out the blank of the main portion *A*, we twist together two or more, and preferably three, wires *w* to form the blank of the hook portion *B*, as illustrated by Figs. 2 and 2^a. We next draw said blank of the hook portion *B* through a draw-plate, which gives it its cylindrical and smooth exterior, and in a great measure prevents it from untwisting, as the original cylindrical form of the wires is thus destroyed. The product of this operation is represented by Figs. 3 and 3^b. The two blanks above described are next fastened together end to end by a rigid and secure joint *j*, which may be formed by hard soldering and compression, as illustrated by Fig. 4. The partly-made temple is then "trimmed," as illustrated by Fig. 5, the diameter of the main portion being merged into that of the hook portion, as aforesaid. The surplus metal may be removed in any approved way. It is now ready to receive the tip *C*, which is securely fastened on the extremity of the hook portion, as by soldering. Finally, the hook portion is bent to the shape represented in Fig. 1, or to any preferred shape. The temples may be made of any suitable metals or alloys, and when of steel may be tempered like ordinary steel temples. The temples may be sold in pairs detached, and may be hinged to frames of any approved construction in the production or alteration of spectacles.

Having thus described the said hook-temples and their manufacture, we claim as our invention and desire to patent under this specification—

1. A spectacle-temple comprising a relatively straight and stiff main portion, a flexible and resilient hook portion composed of intertwined strands and having at the same time a substantially cylindrical and smooth

exterior of a suitable diameter into which the diameter of said main portion is merged, and a terminal tip embracing the outer extremity of said hook portion and fast thereon, substantially as hereinbefore specified.

5 2. The within-described process of making hook-temples, consisting of intertwisting strands of wire to form the hook portion, then drawing the same to render its exterior substantially unbroken and smooth, then fastening the same endwise to the main portion, then trimming both portions, then attaching a terminal tip to secure the strand ends of the hook portion, and finally bending the hook portion to the desired shape, substantially as hereinbefore specified.

10 3. In the manufacture of hook-temples, the process of forming a strong, flexible, and resilient hook portion having a smooth exte-

rior, which consists in intertwisting strands of wire and then drawing the blank through a draw-plate, substantially as hereinbefore specified.

15 4. In the manufacture of hook-temples, the process of merging the diameter of a solid main portion into that of a hook portion composed of intertwined strands, which consists in fastening one end of the hook portion to the outer end of the blank of the main portion, and then trimming the main portion to remove its surplus metal, substantially as hereinbefore specified.

FERDINAND BUCHHOP.
ALFRED J. ALLIBONE.
